UNITED STATES PATENT OFFICE

LEWIS GOTTSSTEIN, OF CHICAGO, ILLINOIS, ASSIGNOR OF ONE-HALF TO CARSON PIRIE SCOTT & COMPANY, OF CHICAGO, ILLINOIS, A CORPORATION OF ILLINOIS

DISPLAY STAND

Application filed July 11, 1931. Serial No. 550,135.

The invention relates to improvements in display stands especially adapted for use in displaying samples of articles for sale, which is of simple construction and highly efficient 5 in use.

Another object of the invention is the provision of improved means for detachably mounting the articles to be displayed on said stand.

10 Another object of the invention is the provision of an improved form of stand proper.

Other objects will appear hereinafter.

The invention consists in the combinations and arrangements of parts hereinafter described and claimed.

15 The invention will be best understood by reference to the accompanying drawing forming a part of this specification, and in which

20 Fig. 1 is a face view of a display stand embodying the invention;

Fig. 2 a detailed face view of the upper portion of a stand with the articles to be displayed removed therefrom;

25 Fig. 3 a section taken substantially on line 3—3 of Fig. 2, but showing one of the articles to be displayed in the process of insertion or removal;

Fig. 4 a side view of the stand; and

30 Fig. 5 a perspective view of one of the articles to be displayed.

The embodiment of the invention illustrated in the drawing comprises a suitable supporting member 10 in the form of a flat, 35 rectangular, boardlike body, having its opposite faces or surfaces adapted for display. Each face of the body 10 is provided with two panels, each having vertical side strips or moldings 11 and top and bottom strips 12, as indicated. The side strips 11 are provided 40 with transversely registering notches or grooves 13 in their inner sides.

The articles to be displayed in the embodiment of the invention illustrated in the drawing 45 are samples of flexible oilcloth 14, said samples being folded or looped, as shown in Fig. 5, the raw edges being secured to a transverse flexible supporting strip 15 by means of wire stitches or staples 16, as indicated. A paper tube or roll 17 is also prefer-

ably inserted in the fold of the sample 14 to cause the lower portion of the sample to extend outwardly from the board 10 and also assume rounded position, thereby augmenting the ornamental appearance presented. 55

The supporting member 10 is provided with transverse feet or brackets 18 to maintain the same in upright position on a floor or the like.

By this arrangement a simple and effective 60

display stand is provided, which is adapted and arranged to display attractively a large number of samples of materials such as oilcloth or other fabrics in an attractive and advantageous way. Obviously, the samples 65

of material may be readily changed when desired by flexing the supporting strips 15 and removing and replacing the ends thereof from and into the notches 13. It will be noted that the notches 13 extend entirely 70

across the inner faces of the strips 11 and that the displayed articles 14 depend from the strips 15 sufficiently to contact with the strips 11 to prevent lateral displacements of the displayed articles. By extending the notches 75

13 entirely across the inner faces of the strips 11, the construction of said strips is greatly facilitated and by utilizing the displayed articles to constitute side stops, lateral dis- 80

placement is prevented due to lateral sliding of the strips 15 through said notches. By adapting both surfaces of the supporting member 10 to display purposes, a large 85

number of samples may be conveniently and advantageously mounted thereon.

While I have illustrated and described the preferred form of construction for carrying my invention into effect, this is capable of variation and modification without departing from the spirit of the invention. I, there- 90

fore, do not wish to be limited to the precise details disclosed, but desire to avail myself of such variations and modifications as fall within the scope of the appended claims.

Having thus fully described my invention, 95 what I claim as new and desire to secure by Letters Patent is:

1. A display stand comprising a supporting member; parallel supporting strips on the face of said supporting member, there 100

being transversely registering notches in the inner faces of said strips; flexible retaining strips traversing the space between said supporting strips and having their ends inserted in said notches; and display articles folded upon themselves and having their upper edges secured to said display strips, said articles depending from said retaining strips to constitute stops to limit insertion of the ends of 10 said retaining strips in said notches.

2. A display stand comprising a supporting member; parallel supporting strips on the face of said supporting member, there being transversely registering notches in the 15 inner faces of said strips; flexible retaining strips traversing the space between said supporting strips and having their ends inserted in said notches; display articles folded upon themselves and having their upper edges secured to said display strips, said articles depending from said retaining strips to constitute stops to limit insertion of the ends of 20 said retaining strips in said notches; and cylindrical objects inserted in the folds of 25 said articles.

In witness whereof, I have hereunto set my hand this 7th day of July, 1931.

LEWIS GOTTSSTEIN.
